Patented Sept. 21, 1976

241,549

MODULAR MEDICAL OR DENTAL OPERATORY UNIT

James E. Rota, 2479 Pesquera Drive,
Los Angeles, Calif. 90049

Filed Nov. 11, 1974, Ser. No. 522,427

Term of patent 14 years

Int. Cl. D24—01

U.S. Cl. D24—1 B

7 2 9.1

Fig. 2

7-2-7

5-19-5FIG. 1 is a top front perspective view of a modular medical or dental operatory unit showing my new design;

FIG. 2 is a top perspective view as seen from the left of FIG. 1;

FIG. 3 is a top plan view thereof;

FIG. 4 is a rear elevation thereof; and

FIG. 5 is a top rear perspective view thereof.

I claim:

The ornamental design for a modular medical or dental operatory unit, substantially as shown.
